ICE CUBE REMOVER

Clifford R. Carney, Miami, Fla., assignor to Nash-Kelvinator Corporation, Detroit, Mich., a corporation of Maryland

Application May 17, 1937, Serial No. 143,162

5 Claims. (Cl. 62—108.5)

The invention relates to an ice cube remover and more particularly to devices for either releasing ice cubes from ice trays or pans or the ice cube racks therefrom and the ice cubes from such racks in a single operation.

The primary object of the invention is the provision of a device of this character, wherein each pocket within an ice cube tray or pan or each space of an ice cube rack as releasably held within the ice tray or pan has associated therewith a releaser for the dislodgment of an ice cube frozen therein so as to enable the removal of the ice cubes either from the pan or tray or from the rack as fitted within the tray or pan and in the latter instance the rack will be bodily extracted from the tray or pan in a single operation of the device thus relieving the tedious and laborious work of the removal of the ice cubes from the tray or pan in the usual well-known manner by subjecting the content of the tray or pan to heat or to hot or cold water flowing from a spigot, faucet or the like or as held within a container.

Another object of the invention is the provision of a device of this character, wherein through the action of a releaser a break can be had within an ice cube preferably at the point where the same has become frozen to the ice tray or pan or the grid or rack as held therein thus effecting an air passage, space or gap in the frozen content of such tray or pan to enable the release of the ice cubes therefrom and the easy and quick removal for the emptying of the tray or pan and a rack or grid as may be contained therein and without any material waste of the ice or unduly breaking the cubes at the time of removal.

A further object of the invention is the provision of a device of this character, wherein the construction in its entirety is novel and in the working thereof eliminates excessive labor on the part of the user for the removal or extracting of ice cubes from an ice pan or tray as employed in refrigerant or ice making machines of the present day type and assuring quick removal of the ice cubes without any appreciable melting of the same.

A still further object of the invention is the provision of a device of this character, which is simple in its construction, reliable and easy of operation, efficient in the working thereof, strong, durable, convenient for use, readily applicable to an ice tray or pan, and inexpensive to manufacture.

With these and other objects in view, the

invention consists in the features of construction, combination and arrangement of parts as will be hereinafter more fully described, illustrated in the accompanying drawings, which disclose the preferred and modified forms of embodiment of the invention, and pointed out in the claims hereunto appended.

In the accompanying drawings:

Figure 1 is a top plan view of a specially formed ice tray or pan showing the device constructed 10 in accordance with the invention applied thereto and of simplified and preferred embodiment thereof.

Figure 2 is a sectional view on the line 2—2 of Figure 1 looking in the direction of the arrows. 15

Figure 3 is a fragmentary top plan view similar to Figure 1 showing the device in a completed releasing position.

Figure 4 is a sectional view on the line 4—4 of Figure 3 looking in the direction of the arrows. 20

Figure 5 is a fragmentary vertical longitudinal sectional view through the device in the position shown in Figures 3 and 4.

Figure 6 is an exploded perspective view of a companion pair of the releasing elements of the 25 device detached.

Figure 7 is a fragmentary plan view showing a slight modification with the device permanently joined with the tray or pan.

Figure 8 is a top plan view showing a further 30 modification.

Figure 9 is a fragmentary vertical longitudinal sectional view thereof.

Figure 10 is a fragmentary plan view of the ice cube grid or rack included in the modified 35 form shown in Figures 8 and 9.

Figure 11 is a fragmentary top plan view of a still further modification of the device.

Figure 12 is a sectional view on the line 12—12 of Figure 11 looking in the direction of the 40 arrows.

Figure 13 is a sectional view on the line 13—13 of Figure 11 looking in the direction of the arrows.

Figure 14 is a fragmentary vertical longitudinal 45 sectional view showing the device adjusted from the position shown in Figure 11.

Figure 15 is a top plan view of the cam slide employed in the modified form shown in Figures 11 to 14.

Figure 16 is a fragmentary top plan view of the rack or grid employed in the modified form shown in Figures 11 to 15.

Figure 17 is a top plan view of a still further 50 modification of the device.

Figure 18 is a sectional view on the line 18—18 of Figure 17 looking in the direction of the arrows.

Figure 19 is a sectional view on the line 19—19 of Figure 17 looking in the direction of the arrows.

Figure 20 is a fragmentary side elevation of the grid removed from the tray or pan.

Similar reference characters indicate corresponding parts throughout the several views in the drawings.

Referring to the drawings in detail, particularly Figures 1 to 6 inclusive, which disclose the preferred embodiment of the invention, A designates generally a specially prepared ice cube tray or pan comprising a sheet metal body 10 flat throughout the upper side thereof and is preferably of substantially rectangular shape having the rounded corners 11 while at opposite sides of the longitudinal center of this body 10 and struck therefrom are transversely spaced substantially circular shaped downwardly tapered ice cube pockets 12, these being of uniform depth and diameter throughout the series or group thereof. Adapted to be associated with this tray or pan A is the ice cube remover which comprises a straight actuator bar 13 to be normally superimposed upon the body A at the longitudinal center thereof for disposition between the transversely disposed pockets 12 of the respective pairs formed in said body 10 while depending within these pockets 12 are releasers in the form of pins 14 provided with inwardly directed upper crank ends 15 at right angles thereto which at their meeting sides or faces adjacent to each other are flat faced at 16 while the remaining outer sides 17 of said crank ends 15 are rounded. The crank ends 15 are adapted in the assembly thereof in the device to be overlapped one upon the other and in this relation to each other are accommodated in a circular hole or opening 18 formed transversely in the bar 13 and loosely fit therein for turning action and are retained by outstruck terminals 19 within said holes or openings 18. The holes or openings 18 are uniformly spaced from each other in the bar 13 and under normal lay of such bar 13 the pins 14 depend at an incline within the pockets 12 in close or contacting relation to the side walls of the said pockets 12 and the lower ends resting upon the bottoms of such pockets for a purpose presently described.

Swingingly supported at one end of the bar 13 is a combined fulcrum and actuating lever 20, being pivoted at 21 to the said bar 13 and is provided with a hook-like fulcruming tip or toe 22 adapted for engagement with a reinforced end area 23 formed on the tray or pan A at the longitudinal center of its body 10. This lever engaging the end 23 of the tray or pan A when swung vertically in an upward direction actuates the bar 13 for the shifting thereof and under this action through the crank ends 15 journaled in the holes 18 in said bar causes a rotation to the pins 14 and simultaneously therewith the said pins 14 are swung vertically from their normal inclined position to a substantially perpendicular or upright position within the pockets 12 of the tray or pan A. This rotation of the pins 14 when the content of the pan or tray has become frozen causes a breaking away of the ice therefrom and creating within the ice cubes interstices or air passages and in this manner quick release and removal of the ice cubes from the pan or tray may be had. The swinging activity

of the pins 14 simultaneously with the rotation thereof imparted thereto from the crank ends 15 on the shifting of the bar 13 applies a pressure to the ice cubes and a shearing-like action of the pins thereon for dislodgement of the ice cubes within the pockets 12 so that the same can be readily removed or extracted therefrom. Air admitted through the interstices or passages created by the pins 14 of the device assures a quick freeing by disruption of the adherence of the ice with the walls of the pockets for the release of said cubes. During the rotary and swinging activity of the pins 14 the tip or toe 22 of the lever 20 has fulcrum action on the area 23 and thus vertical swing is imparted to the pins in that the bar 13 under longitudinal sliding thereof by reason of its pivotal connection 21 with the said lever gradually rises from normal superimposed position upon the top of the pan or tray A, the crank ends 15 being acted upon by the bar 13 for scissor-like motion and thus rotation of the pins 14 will be had.

In Figure 7 of the drawings there is shown a slight modification of the invention, wherein the pockets 24 for the ice cubes are of substantially squared formation or flat walled as at 25 in contradistinction to the circular formation of pockets 12 hereinbefore described.

In Figures 8, 9 and 10 of the drawings there is shown another modification of the invention, wherein the ice tray or pan 26 has removably fitted therein an ice cube rack or grid 27 formed with the longitudinal and transverse dividing partitions or separators 28 and 29, respectively, for the formation of the ice cubes and rising from this grid or rack 27 at its longitudinal center are pivot ears 30 and 31, respectively, the latter ear having pivoted at 32 thereto a link 33 while pivoted at 34 to the ear 30 is an actuator and fulcrum lever 35, the latter and the said link 33 being pivoted at 36 to a shift bar 37 identical in the working thereof to the bar 13 for actuating the releaser pins 38 similar to the pins 14. This lever 35 has a fulcrum toe or tip 39 for engagement with the end reinforcement area 40 of the pan 26 so that on initially actuating the lever 35 the pins 38 will be rotated and swung vertically for the freeing or releasing of ice cubes within the rack or grid 27 and on further movement of the lever 35 the toe or tip 39 fulcrums at the area 40 on the pan for the bodily lifting of the rack or grid 27 from the said pan 26 and in this manner the rack or grid is removed from the pan and the ice cubes released from the rack or grid for their quick and easy removal from within the pan or tray.

In Figures 11 to 16 inclusive of the drawings there is shown a still further modification of the invention, wherein the pan or tray 41 has permanently formed therein the transversely arranged spaced dividers or partitions 42 integral with the longer side walls of said tray or pan while saddling the said partitions or dividers 42. At the longitudinal center of the tray or pan is a center divider or grid 43 having the notches 44 opening through the bottom edge thereof for accommodating the dividers or partitions 42 and in this manner separating the pan into ice cube pockets 45 while at one end of this divider 43 and at its top edge is a pivot eye or ear 46 accommodating a pivot 47 for a combined actuator and fulcrum lever 48 adapted to swing vertically and pivotally linked at 49 to a cam slide 50 superimposed upon the divider 43 at its top edge and slidably connected thereto at 51 and this

slide 50 next to the ear or eye 46 is slotted at 52 to provide a way for the said ear or eye 46 on the shifting of the slide 50 upon the center grid or divider 43. In this manner the slide 50 is guided longitudinally on the grid or divider 43. Formed next to the lowermost edge of the divider 43 and at opposite sides thereof are bearings 53 in which are journaled laterally swinging releasers, each in the form of a single length of stiff 10 wire 54 bent on itself to provide straddling yokes 55 bridging the transversely disposed partitions or dividers 42 and constituting releasing fingers, these being engaged in diagonally disposed cam slots 56 formed in the cam slide 50. Each wire 15 54 at each end 57 is upturned and engaged in a diagonal cam slot 58 in the slide 50. Thus when the slide 50 is shifted, it causes the swinging of the releasers by reason of the engagement of the yokes 55 in the cam slots 56 and the ends 57 in the slots 58 thus acting upon the ice cubes adhering to the partitions or dividers 42 for breaking loose such ice cubes within the pockets 45 in the tray or pan 41. The yokes are arranged close 20 or in contacting relation to the partitions or dividers 42 and on the breaking of the ice cubes air cavities or passages are formed in the ice so as to enable the removal or release of the ice cubes from the pockets 45 with dispatch. The cam slide 50 is actuated by the lever 48 which 25 30 has a fulcrum tip or toe 59 for contact with an end next thereto of the tray or pan 41 so that the center grid or divider 43 can be bodily lifted out of the tray or pan subsequent to the release of the ice cubes within the pockets 43 therein.

It is, of course, understood that in lieu of having the dividers or partitions 42 integral with the pan these can be made integral and projected laterally from opposite sides of the center grid or divider 43 and thus effecting a releasable rack or grid for the tray or pan.

In Figures 17 to 20 inclusive of the drawings there is shown a further modification, wherein certain of the yokes 60 constituting the releaser fingers are formed with finger grips 61 so that the releasers can be manually operated by pressing the grips 61 toward each other and thus the lever and cam slide hereinbefore described may be entirely dispensed with. The wires 62 from which are bent the yokes 60 are journaled at 63 at opposite sides of the center divider or grid 64 similarly to the releasers constituted by the wires 54 in Figures 11 to 13 in the drawings. It is preferable to have the grips 61 located slightly removed from the opposite ends of the center grid or divider 64.

In the use of the device the ice cubes contained within a tray or pan now employed in ice making machines or refrigerators can be readily and quickly released or removed with minimum energy on the part of an operator of the device and also the rack or grid removably seated within the tray or pan can be bodily lifted or extracted therefrom.

The working of the releasers is practically a shearing action on the iced content of a tray or pan and might be effectual for the release of the cubes or the freeing thereof due to the proximity of the releasers to walls next thereto 5 of the pan or tray or the rack or grid and a metal to metal activity or relationship of the device and tray or pan or rack or grid.

The yokes 55 and 60, respectively, are normally inclined within the tray or pan and are 10 moved to a perpendicular or vertical position for shearing action upon the ice content of the said tray or pan and in this manner effecting quick removal or release of the ice cubes therefrom.

What is claimed is:

1. An ice cube remover for ice trays having a plurality of separated ice pockets, comprising movable members depending within the pockets close to walls thereof and adapted to be disposed normally at an incline and shiftable to a substantially perpendicular position, and means active upon said members for imparting motion thereto.

2. An ice cube remover for ice trays having a plurality of separated ice pockets, comprising 25 movable members depending within the pockets close to walls thereof and adapted to be disposed normally at an incline and shiftable to a substantially perpendicular position, and a lever having connection with said members for imparting 30 motion thereto.

3. An ice cube remover for ice trays having a plurality of separated ice pockets, comprising 35 movable members depending within the pockets close to walls thereof and adapted to be disposed normally at an incline and shiftable to a substantially perpendicular position, a lever having connection with said members for imparting motion thereto, and a fulcrum on said lever and active upon the tray for cooperation of said lever with the members for releasing effect thereto from the frozen content of the tray.

4. A device of the character described comprising a plurality of releasers for engagement in frozen content of an ice tray, a shiftable bar active upon said releasers to impart movement thereto in unison with each other, a lever operating said bar, means on the lever for fulcrum action with the tray, means associated with said releasers for effecting rotation and swinging movement thereto under the action of said bar, and a cube-forming grid associated with the said lever and releasers and releasably fitted in the tray and bodily movable under the fulcrum action of said means.

5. A device of the character described comprising a grid for fitting an ice tray, releasers swingingly connected with said grid and operative for freeing the frozen content of the tray, means for imparting movement to the said releasers, and means for rotating the releasers concurrently with the swinging movement thereof.

CLIFFORD R. CARNEY.
